EMERSON A. GILBERT, OF JAMESTOWN, NEW YORK.

PHOTOGRAPHIC DEVELOPING-PAPER HOLDER.

SPECIFICATION forming part of Letters Patent No. 689,300, dated December 17, 1901.

Application filed November 12, 1900. Serial No. 36,185. (No model.)

To all whom it may concern:

Be it known that I, EMERSON A. GILBERT, a citizen of the United States, residing at Jamestown, in the county of Chautauqua and State 5 of New York, have invented a new and useful Photographic Developing-Paper Holder, of which the following is a specification.

The quick-developing papers now in use for printing-out purposes and which for many 10 reasons are greatly preferred by photographers demand such strong and poisonous developing solutions that many operators are deterred from using them, the solutions eating the fingers and producing great cracks, 15 which are almost non-healing.

The object of my invention is to provide a simple and convenient holder or dipper for the damp paper, whereby the hands of the operator need not enter the developing solution 20 and upon which the damp paper may lie flat, the low sides of the flat bottom of the dipper allowing the easy dipping in the solution, yet preventing the paper from floating off the holder. It is essential that the developing-surface of the paper shall not be touched 25 by a clasp, a finger, or any object while in the developing solution or while the paper is damp therewith, or finger-marks and stains will be the result. My holder allows the paper to develop clean to the edge, and a finger-hole allows 30 of the easy removal of the paper from the holder without touching the developed or upper surface. I attain this object by my device as shown in the accompanying drawings, 35 in which—

Figure 1 is a perspective view of my holder with the paper in position for developing. Fig. 2 is a plan view of my holder with solid flat bottom, as I usually make it. Fig. 3 is a 40 plan view of holder with perforated bottom.

10 is the handle of the holder, which may be made in any strong and suitable manner which shall keep the fingers out of the solution.

45 11 is the flat bottom of the holder, which I make solid for most purposes, since perforations like 12 or a sieve bottom sometimes form bubbles in the solution and do not do even work.

50 13 is the side of the flat bottom, which is made low, from a sixteenth to an eighth of an inch serving my purpose, which is to hold the damp paper on the flat bottom and allow it to be easily and quickly dipped in the so-

lution and to hold a thin even body of the solution on the paper, which is then drained off and the holder is dipped in the bath. 55

I prefer to make finger-hole 15 in the end of the flat bottom opposite the handle, since my holder can then be used with equal ease 60 by a right or left handed operator, and finger-hole 15 should be made sufficiently large for the finger-tip to be inserted under the paper to lift the same from the under side, for in using my holder the wet paper is spread on 65 the flat bottom with the developing side up. It is then dipped with a steady hand in the developing solution, allowing the developer to flow evenly over the surface of the paper. After draining it is dipped in the bath and 70 quickly raised by the finger-tip from the under side, the wet paper sticking to the finger and the finger not touching the upper surface of the paper, thus preventing all stains or the rucking of the paper in taking it from the 75 holder.

I make my holder of aluminium, hard rubber, or other neutral material which will not injure the chemicals of the solution. The low sides might be cut at different points to 80 aid in draining the paper; but I find that the solution easily drains over the low sides 13 and through the finger-hole 15 and the closed sides better hold an even body of the solution on the paper. 85

Some operators prefer to pour the solution over the paper instead of dipping the paper in the solution. This is more easily accomplished with my holder than in a large tray, since it is only necessary to pour the solution 90 evenly over the paper on the flat bottom and then spread it with a gentle motion of the holder, after which drain off.

I claim as new—

In a photographic developing-paper holder, 95 a solid flat bottom 11 having a recess 15 in one edge, a handle 10 at one side of said bottom, the remaining edges of said bottom having the low upturned sides 13 to keep the paper thereon, substantially as shown and for 100 the purpose specified.

In testimony whereof I have signed my name to this specification in the presence of two subscribing witnesses.

EMERSON A. GILBERT.
